UNITED STATES PATENT OFFICE.

ABNER R. NEFF, OF LONG BEACH, CALIFORNIA.

CAN OPENER.

Application filed November 3, 1920. Serial No. 421,572.

To all whom it may concern:

Be it known that I, ABNER R. NEFF, a citizen of the United States, residing at Long Beach, county of Los Angeles, State 5 of California, have invented new and useful Improvements in Can Openers, of which the following is a specification.

This invention relates to a can opener and an object of the invention is to provide an 10 improved device of this character.

In general the can opener provided by the present invention is of the character set forth in my copending application entitled Can opener, filed October 13, 1919, Serial 15 Number 330,456, and although the present invention is in no way limited or restricted to any one particular class or kind of can opener, it is particularly adapted for use in connection with can openers of the 20 character set forth in said copending application.

It may be stated that a particular and noteworthy feature of the present invention is the cutter or blade. The general shape of 25 the blade is such as to cause it to follow and to cut at the edge of the can, while the cutting edge is such as to effectively and smoothly cut the metal of the can. The cutting or sharp edge is formed on the blade 30 by a slight bevel at the side of the blade which engages the side of the can and a comparatively large bevel at the other side of the blade. The edge thus formed is a knife edge sufficiently sharp to effectively cut 35 sheet metal such as cans are ordinarily made of. Small notches or indentations are formed in the knife edge along its entire cutting portion. These notches are particularly effective in preventing slippage of the sharp 40 cutting edge over the metal without cutting it and also materially assist the sharp cutting edge in actually cutting the metal.

The general construction of the device is of particular note in that it is neat and 45 sanitary, and permits of simple and inexpensive manufacture. The device is formed of two pieces, a handle and a blade, welded together to form a continuous structure.

The welding together of the blade and 50 handle saves several operations in the process of manufacture and produces a device which cannot become loose or disconnected and which can be easily kept clean and sanitary. The absence of screws, rivets, etc., is 55 accompanied by an absence of cracks and corners such as would accumulate dirt and

which would need cleaning out. The sanitary feature of the welded construction is in itself particularly important and lends great commercial value to the device. 60

The various objects and features of the invention will be best and more fully understood from the following detailed description of a preferred embodiment of the invention throughout which reference is had 65 to the accompanying drawings, in which—

Fig. 1 is a bottom plan of the device; Fig. 2 is a side elevation of the device; Fig. 3 is a top view of the device; Fig. 4 is an enlarged edge view of the blade or cutter 70 showing it as viewed in Fig. 1; Fig. 5 is an enlarged side elevation of the blade or cutter viewing it as it is viewed in Fig. 2; and Fig. 6 is an enlarged detailed sectional view of the blade taken as indicated by line 6—6 75 on Fig. 4.

Throughout the drawings numeral 10 designates the handle of the opener to which is connected the blade 11. Various forms of handle construction can be advantageously used in the construction of the opener but it is preferred that the handle be formed from a single piece of strip metal or ribbon stock. In the preferred form of the handle 10 a single strip of metal is bent 80 or looped so that the blade 11 is held between its end portions 18 and 19. The portions 12 and 13 of the strip of metal form the handle or that portion of the device adapted to be gripped by the hand of the 85 operator. The shape or curvature of the portions 12 and 13 is such as to form a convenient and comfortable handle to be gripped by the operator. From inspection 90 of the drawings it will be seen how the portions 12 and 13 form a complete loop, or in other words how the strip of metal is bent or shaped so that it comes together at A. 95

In accordance with the present invention the two portions of the strip of metal are 100 welded or otherwise fused together at A making the handle portion, formed by portions 12 and 13, a complete continuous flattened loop.

Between the looped portion of the handle 105 just described and the end portions 18 and 19 of the strip of metal which engage the blade 11 there is a second smaller looped portion formed by outwardly bent portions 16 and 17 of the strip of metal. This small 110 looped portion forms a very convenient and comfortable brace for the thumb and fore-

2 finger of the operator when he is manipulating the device. In practice this small looped portion prevents the hand of the operator from slipping forward on the handle and enables him to get a firm grip or purchase on the handle. The two end portions 18 and 19 are flat and parallel with each other and carry the butt portion 20 of the blade 11 between them. As provided 5 by this invention the two side portions 18 and 19 of the strip of metal and the butt portion of the blade 11 are positively and permanently fused or welded together. The fusing together of these parts makes the 10 blade practically a continuation of the handle and thereby renders the device particularly strong, rigid and durable. In the preferred form of the invention the end portions 18 and 19 and the butt portion 20 are 15 electrically spotwelded together as such method is inexpensive and particularly effective. It is also preferred that the joint at A be electrically spotwelded for the reason just mentioned. It is perfectly obvious 20 how the fusing or welding of the joints of the device produces not only a strong rigid structure but also provides a neat sightly and sanitary device. With fused or welded joints or connections there are no projecting parts to form corners such as would 25 catch dirt and need frequent cleaning. This is an important point from a practical standpoint and is therefore considered of particular note.

30 35 The blade 11 extends from the end portions 18 and 19 and is shaped so that its outer portion 21 is pointed. The blade 11 is transversely curved, is of uniform thickness throughout its entire length, and is 30 formed with a sharp cutting edge 22 at one of its edges. From the drawings it will be noted that the cutting edge 22 is curved from the butt end of the blade to the point 21 and that it is a knife edge, or a sharpened 40 edge, formed by a comparatively large bevel 22^a on one side of the blade and a comparatively small bevel 22^b at the opposite side of the blade. This manner of forming the cutting edge causes it to be closer to the side 45 B of the blade than it is to the side C. The cutting edge is not smooth but is made irregular or notched by running a knurling tool over it before it is tempered or hardened. It will be readily understood how the 50 55 passing of a knurling tool over the edge 22 will form a plurality of dents or notches 22^c in it as clearly shown throughout the drawings. These notches 22^c are not deep or large and are not such as to spoil the cutting 60 65 edge formed by the bevels 22^a and 22^b. The notches 22^c are provided primarily to prevent slippage of the blade on the metal being cut by it although they actually have more or less of a file action and materially assist in cutting the metal of the can. In the

70 practical operation of the device the combined action of the sharp edge and the notches is such as to cause the blades to feed into and effectively cut the metal of a can.

In the practical manufacture of the blade 75 the bevels 22^a and 22^b are formed by grinding, the notches 22^c are formed by knurling, and the blade is pressed and bent to have the proper transverse curvature. The blade is then tempered or hardened. It will 80 be understood of course that the invention is in no way limited or restricted to any particular method or process of manufacture and that therefore the bevels 22^a and 22^b may be formed by other methods than by grinding and that the notches 22^c may be formed in manners other than knurling. I am herein referring to the notches being formed by knurling merely because that is 85 the way they are actually and practically formed and because they are preferably of the character produced by a knurling operation.

90 The end 25, of the strip of metal which forms the handle 10, extends or projects from the end portion 19 and is provided with a rounded end 26 spaced somewhat from the side B of the blade 11. The side B of the blade 11 is the inner side of the 95 blade, thereby causing the end 26 to engage the end of the can being removed or cut out by the device. From inspection of the drawings it will be seen that the formation or shape of the end 25 is such as to form a 100 space 27 between it and the blade 11 into which the edge of the end of the can may extend or curl when it is cut. In practice it is preferred that the space 27 of such size as to allow the end of the can to curl slightly due to the cutting but is not large enough to allow it to curl so as to endanger 105 the hand of the operator.

110 When the device is in operation the side or surface B of the blade 11 is kept tightly or close against the inner surface of the side wall of the can by projection 40 which extends from the end portion 18 in the manner clearly shown in the drawings. The projection 40 extends from the end portion 18 so that the upper edge of the side wall of the can extends between the projection 40 and the blade 11 and is engaged by both the blade and the projection. The shape or curvature of the projection 40 is 115 such as to form a tapered or V-shaped groove 42 between it and the blade 11, as clearly shown in the drawings. With this construction downward pressure on the handle 10 (which causes cutting of the end of the can) causes the edge of the side wall of the can to wedge between the projection 40 and the blade 11 and thereby prevent slipping of the opener on the edge of the can when the blade 11 is cutting and 120 also forms the fulcrum or pivot of the 125 130

opener. The side C of the blade being held close against the inner side of the wall of the can causes the end of the can to be cut where it joins the wall of the can without leaving a flange or inwardly extending edge. It will be understood how the cutting operation may be started in the common or ordinary manner, that is, the point 21 of the blade may be forced or pumped through 10 the top of the can at or near the edge of the side wall thereof. Downward movement of the handle 10, when the device is in a more or less vertical position will cause upward movement of the blade 11 and will 15 thereby cause the edge 22 to cut the end or top of the can. When the end or top of the can has been removed by the present device the contents of the can may be easily emptied from it without danger of the operator being cut or injured by the cut edge 20 of the can.

In the preferred form of construction the blade 11 is not flat but is transversely curved so that the side B is convex and the side D concave, as clearly shown throughout 25 the drawings. It will be noted particularly in Figs. 1, 3 and 4 of the drawings, that the concavity of the blade is produced by bending or curving it adjacent to the butt portion in the direction indicated by the arrow E and bending or curving it at the outer portion in the direction indicated by arrow F. It has been found in practice that 30 a blade when bent or formed in this manner will follow very closely the wall or side of the can and will cut the top very close to the side of the can. It will be understood however that the amount that the blade is bent as indicated by the arrows will depend upon the circumstances under which it 35

is to be used or upon the general size of can upon which it is to operate. It has been found in practice that the curvature shown in the drawings is satisfactory for cutting the average or ordinary sized can 45 used in packing foodstuff or the like.

Having set forth only a preferred embodiment of my invention I do not wish to necessarily limit or restrict myself to the specific details hereinabove set forth but 50 I wish to reserve to myself any variations that may appear to those skilled in the art or that may fall in the scope of the following claims.

Having described a preferred form of 55 my invention, I claim:

1. In a can opener, a blade having a sharp edge and formed with a plurality of relatively fine notches in and substantially confined to its sharp edge. 60
2. In a can opener, a blade having a knurled sharp edge.
3. In a can opener, a blade having a relatively finely knurled sharp cutting edge.
4. In a can opener, a blade having a relatively finely knurled cutting edge formed relatively close to one side of the blade by different sized bevels at the two sides of the blade. 65
5. In a can opener, a transversely curved 70 blade having a sharp edge and formed with a plurality of relatively fine notches in and substantially confined to its sharp edge.

In witness that I claim the foregoing I have hereunto subscribed my name this 75 30th day of September, 1920.

ABNER R. NEFF.

Witness:

VIRGINIA BERRINGER.
